UNITED STATES PATENT OFFICE.

DANIEL NELSON, OF OAK PARK, ILLINOIS, ASSIGNOR TO MARSHALL FIELD & COMPANY, OF CHICAGO, ILLINOIS, A CORPORATION OF ILLINOIS.

METHOD OF PACKAGING MERCHANDISE.

Original application filed April 6, 1925, Serial No. 20,926. Divided and this application filed January 8, 1926. Serial No. 79,950.

This application is a division of my application filed April 6, 1925, Serial No. 20,926, describing a novel package of merchandise, and a method of producing the same, according to which a paper bag accurately fitting within a packing frame, and sustained thereby, has moulded within it or between its sides and an article of merchandise to be enclosed therein, a mass of packing material 10 pressed into the space with sufficient density to mould it, on the interior to the form of the article of merchandise and on the exterior to the form of the sustained paper bag; the packing material having the inherent quality of retaining the shape to which it is moulded so that the paper bag which will be closed around the completed mass of moulded packing material will be required to withstand stresses which are substantially limited to the direction of tension, and the bag, in addition to serving as the means for sealing the package, need only function as a means for preventing the moulded packing mass from disintegration by contact with other objects.

The present invention relates to the aforesaid novel method of packaging merchandise.

In order that the invention may be fully understood, an illustrative embodiment thereof will now be described with reference to the accompanying drawings, in which

Figure 1 is a perspective view showing a packer's bench with a supply of envelopes, a packing frame containing a bottom block, and a supply of packing material;

Figure 2 is a fragmentary view showing a portion of one of the envelopes of Figure 1 in partially open condition;

Figure 3 is a view showing an envelope in completely opened position;

Figure 4 is a perspective view illustrating the packing frame and an envelope in assembled relation, and an article of merchandise in process of being packed within the same;

Figure 5 is a perspective view of a package produced in accordance with the present invention and ready for shipment;

Figure 6 is a view of a knock-down packing frame in collapsed condition; and

Figure 7 is a perspective view showing a modified construction of envelope.

Referring to the drawings, which disclose instrumentalities employed in practicing the new method, A represents a packing or molding frame, B a stack of envelopes, preferably paper bags, for use within such frame, and C a supply of packing material of known kind, for instance, excelsior or equivalent mouldably and inherently resilient material in fibrous form, for use in filling the space between the envelope and the article of merchandise. Frame A may consist preferably of sides 1, 2, 3 and 4, with hinging connection 5 between at least two sides, for instance, the sides 2 and 3, although two of the other corners may also be of hinging construction, for instance, as shown at 6, where the sides 1 and 2 meet, and at 7 where the sides 3 and 4 meet, the fourth corner 8 involving in its construction some suitable form of releasable connection, for instance, a hasp and staple connection. If the frame is made of metal as shown, the hasp may take the form of a projection 9, integral with the side 1, and adapted to lap over the adjacent end of the side 4, said projection having a slot 10 adapted to receive the staple 11 after the manner of a hasp and thereby hold the packing frame in service position while leaving the connection readily releasable for opening up the frame when the package is completed. The hinged corners of the frame A may also be provided with justifying stops 12, 13 and 14, each made to project rigidly from one wall, for instance, by bending up a part of the wall material, in position to receive abutment of the other wall involved in the hinge connection, and thereby cause the walls to assume rectangular relation when the frame is set up.

Each envelope B comprises, besides its bottom (not shown), sides 15, 16, 17, and 18 united therewith, as well as with one another, in a manner to provide, when the envelope is distended, five sides of a rectangular closure, the sixth side of which is left open for receiving the merchandise and packing material, but adapted to be closed by means of flaps 19, 20, 21, and 22 projecting from the upper margins of said sides. As originally supplied, the envelopes will be folded in a manner to render them convenient for opening and distension, and preferably, also in a manner to develop the loca-

tion of bending to develop the square bottom fitting the frame; as, for instance, by folding the sides in the manner usual in supplying paper bags in collapsed form, and as suggested in Figure 2, and additionally creasing the bag to indicate all four margins of the bottom, conformably to the horizontal dimensions of the packing frame. The frame A, having been set up as suggested in Figure 4, and being selected from a supply of such frames of different sizes in order to conform substantially in dimensions with the envelope that is being used, the envelope is introduced within the frame and its closing flaps folded outwardly, as shown in Figure 4, and the packing material and merchandise are introduced and solidly pressed into the space defined by the envelope, but sustained by the rigid packing frame until the packing material becomes a moulded mass, the packing being, of course, disposed in a manner to thoroughly protect the merchandise, and the flaps 19, 20, 21, and 22 are then folded inward over the now solid mass, within the envelope, and secured by adhering an uppermost flap, for instance, the flap 22, to the flap which immediately underlies it, if one or more of the flaps are gummed on their margins, for instance, as suggested by the marginal shading on the flaps of Figure 4; or, if desired, secured by means of a separately formed gummed strip; also, if desired, by causing hold-down tabs 22^a, provided on one of the side flaps, for instance, the flap 22 as shown in Figure 4, or as extensions of the separately formed gummed strip, to adhere to the ends of the envelope, the hasp-latch 10, 11, being in the meantime released and the packing frame opened sufficiently to admit the said end tabs. Sealing tabs 22^a may or may not be incorporated in the form of the envelope. When used, they may be included in the construction of the flaps without waste of material by appropriately cutting the envelope blank and leaving notches in the end of the flaps 19 and 21 (Figure 4).

In order to adapt the frame A to give shape to packages of different vertical dimension, any one of a series of blocks similar to the block 23 (Figure 1) may be introduced into the frame to constitute a false bottom therefor. While but one of these blocks is shown, it is to be understood that a plurality of the same will be conveniently available to be introduced, selectively, into the situation referred to, and for the purpose stated. While the flaps 19, 20, 21, and 22 are shown as being of definite width and extending from envelope side walls of definite height, which may bring the hinging line of the flaps at a level above the upper margin of the side walls of the packing frame A, especially when a filling block is introduced to vary the depth of the frame, it is to be un-

derstood that the folding line of the flaps can readily be re-established to coincide with the vertical dimension of the package, gauged by the frame, by merely tearing the flaps down at the corner edges until the tearing is arrested by the rounding of the flap over the edge of the frame. Similarly, if the separation of the corner edges of the side walls in producing the flaps leaves the integrity of the side walls ending at a lower level than the sides of the frame, the sustaining relation of the side walls of the frame to the sides of the envelope will nevertheless establish a folding line for the flaps at the packing level defined by the depth of the packing space within the frame.

With all of the corners hinged as described, the packing frame A is adapted to be collapsed into the condition shown in Figure 6 in order to render it more convenient for storage where a plurality of frames of different dimensions are to be kept within selective reach of the operator.

If desired, instead of using flaps 19, 20, 21, and 22 as the closing means for the envelope, the envelope may be in the form shown in Figure 7, where the closing means consists of a wall extension 24 gathered upon the upper portion of the bag by a reverse fold, after the manner of a cuff, so as to avoid hindrance to the packing operation, and presenting the edge for convenient prehension and withdrawal as soon as the packing is finished in order to provide folding portions to the walls in forming a closure similar to that usually resorted to in closing a paper bag, and which may, of course, be secured in any approved known manner.

From the foregoing description it will be seen that a package which ultimately relies upon a light and cheap outer jacket or envelope of paper or other suitable material, can be packed with the same effectiveness and with the same security as in a box made of wood or other rigid material, opportunity being thus afforded for building an effective protection around the merchandise in the form of a solid mass which resists external forces. It is possible to rely on such a thin, cheap enveloping means for the reason that the packing material is moldable and retains its form and stresses imposed upon the envelope are mainly in the direction of tension.

I claim:

1. The improvement in the art of packaging articles of merchandise for shipment, which consists in introducing the article into a tensionally strong flexible envelope, and, while sustaining the envelope in a moulding frame, packing the space between the article and the surrounding envelope with a mouldable packing material, under pressure sufficient to give to the mass a self-sustaining form corresponding to that of the moulding frame, and then, while maintaining com-

pression of the packing, closing and securing the envelope and leaving its walls under tension.

2. The improvement in the art of packaging articles of merchandise, for shipment, which consists in fitting into a moulding frame, a paper bag having an end-closure, inserting the article to be packaged into the bag, packing the space defined by the ar-

10 ticle and the bag, with mouldable packing material, under pressure sufficient to develop a self-sustaining form in the mass, and then, while maintaining compression of the mass, closing and securing the end-closure and leaving the bag under tension.

15 Signed at Chicago, Illinois, this 29th day of December, 1925.

DANIEL NELSON.
